(57) CLAIM

The ornamental design for a kick-boxing exercise device, as shown and described.

DESCRIPTION

FIG. 1 is a perspective view of a kick-boxing exercise device shown supported on a support base pictured in dot-lines; FIG. 2 is a front elevational view of the kick-boxing exercise device of FIG. 1;

FIG. 3 is a right side elevational view of the kick boxing exercise device of FIG. 1, the left side being a mirror image thereof;

FIG. 4 is a rear elevational view of the kick-boxing exercise device of FIG. 1;

FIG. 5 is a top view of the kick-boxing exercise device of FIG. 1; and,

FIG. 6 is a bottom view of the kick boxing exercise device of FIG. 1.

The broken line showing in FIGS. 1-6 is for illustrative purposes only and forms no part of the claimed design.
